UNITED STATES PATENT OFFICE.

ARTHUR ROBERTS, OF EVANSTON, ILLINOIS.

RECUPERATIVE FOUNDATION FOR COKE-OVENS.

1,197,306.

Specification of Letters Patent.

Patented Sept. 5, 1916.

Original application filed December 4, 1914, Serial No. 875,503. Divided and this application filed January 3, 1916. Serial No. 69,996.

To all whom it may concern:

Be it known that I, ARTHUR ROBERTS, a citizen of the United States, residing at Evanston, county of Cook, and State of Illinois, have invented certain new and useful Improvements in Recuperative Foundations for Coke-Ovens, of which the following is a specification.

This application is a division of my co-pending application for Letters Patent of the United States on improvements in recuperative coke ovens, Serial No. 875,503, filed December 4, 1914. In that application, there is disclosed a coke oven construction in which recuperator walls are placed between the adjacent heating walls of the adjacent coke ovens of a bench, and that application relates generally to constructions in which the said recuperator walls are independent of the heating walls to the extent that they may expand and contract independently of the heating walls, and to the extent that they may be constructed or maintained as independent elements or portions of a bench of coke ovens. That application also disclosed a construction of foundation and waste gas flues wherein and whereby heat may be recuperated in said foundation from the waste gas flues.

This application relates to a type of foundation and flue construction wherein and whereby the waste heat contained in the gas traversing the flues may be recuperated in the walls or body of said flues and returned to the burners through the medium of preheated air.

The recuperator principle is one in which heat is constantly delivered from hot gases through a wall or the like to the air or gases traveling separately or independently of the hot gases from which the heat is extracted. That is to say, there is a substantially constant input of heat units into one portion of the structure, and a corresponding, substantially simultaneous, withdrawal of heat units from the other portion of the structure. The rate at which the heat will be delivered into or withdrawn from said structure depends, among other things, upon the intimacy of contact of all portions of the heat carrying medium, or the heat extracting medium, with said structure.

I have discovered the fact that, if the air or other gas be allowed to travel in a substantially unobstructed manner along

the structure, there will form a layer or coating of substantially inert air or gas on the surface of said structure, which layer or coating of air or gas will effectively insulate or cut off the body of the air or gas from the structure. On account of the comparatively high heat insulating quality of this layer of air or gas, the transfer of heat to or from the structure will be very seriously impeded and, consequently the recuperating capacity per unit of superficial area of the structure will be correspondingly lowered.

One of the objects of this invention is to provide one or more spent gas flues of such construction that the incoming air or gas may travel through and within the body of one or more walls of said flue or flues in such a manner that the air or gas will be driven with great frequency and violence against portions of the wall construction to thereby bring all portions of the air or gas into direct and forcible contact with the structure one or more times and at one or more points during the travel of the air or gas. That is to say, the main object of the invention is to so construct the walls of the flue that the transfer of heat into the air or gas traveling through said walls will be occasioned largely by the impingement principle disclosed in my co-pending application for Letters Patent of the United States on improvements in the art of heating, Serial No. 43,753, which was filed August 5, 1915.

Another object of the invention is to so construct the walls of said flue that the walls can be built from a minimum number of block forms. Also to so construct said walls that they will be provided with a mesh of impingement passages contained within its body portion in combination with openings or passages suitably disposed with respect to said mesh to secure a desired transfer of air or gas to and from the mesh.

Other objects and uses of the invention will appear from a detailed description of the same which consists in the features of construction and combinations of parts hereinafter described and claimed.

Referring to the drawings: Figure 1 shows a plan view of a foundation for a bench of coke ovens, said foundation being provided with flues embodying features of the present invention; Fig. 2 is a vertical

section taken on the line 2—2 of Fig. 1, looking in the direction of the arrows; Fig. 3 is a vertical section taken on the line 3—3 of Fig. 1, looking in the direction of the arrows; Fig. 4 is a fragmentary enlarged detail of one corner of the lower portion of the foundation structure, being a section taken on the line 4—4 of Fig. 6, looking in the direction of the arrows; Fig. 5 is a detailed fragmentary view of that corner of the lower portion of the foundation diagonally opposite to the corner shown in Fig. 4, and is a section taken on the line 5—5 of Fig. 7, looking in the direction of the arrows; Fig. 6 is an enlarged fragmentary detailed vertical section corresponding to Fig. 4, being taken on the line 6—6 of Fig. 4, looking in the direction of the arrows; and Fig. 7 is an enlarged fragmentary detailed vertical section corresponding to Fig. 5, being taken on the line 7—7 of Fig. 5, looking in the direction of the arrows. Figs. 6 and 7 may also be considered as being taken on the lines 6—6 and 7—7 of Fig. 1, looking in the direction of the arrows.

Referring to Fig. 2, the same is a section taken through the center portion of carbonizing chamber 8, said carbonizing chamber being one of the chambers of the bench of ovens. It will be understood that a section through the foundation immediately beneath each carbonizing chamber would be similar to the section shown in Fig. 2. Immediately beneath each carbonizing chamber is the transversely extending sole passage 9, and beneath each of said sole passages is a corresponding spent gas channel 10. Each sole passage connects with a corresponding channel by means of a plurality of vertical connections 11, so that the spent gases from the heating walls of each oven collect in the corresponding channel 10.

Referring to Fig. 1, it will be seen that there are the spent gas flues 12 and 13, which extend lengthwise of the bench beneath its side portions, these flues extending along beneath the end portions of the several ovens. The flues 12 and 13 deliver their spent gases to the common connection 14 from which the spent gases may be withdrawn in any desired manner. Each of the channels 10 delivers its spent gases to the flues 12 and 13 by means of the down-comers 15 and 16, respectively, said down-comers being connected to the flues by means of the openings 17 and 18. The construction thus far described is shown in my issued Letters Patent of the United States No. 1,132,685, issued to me as inventor, March 23, 1915, and I will not describe the same at greater length at this point. Adjacent to the lower portion of each coke oven, there is a transversely extending air channel 19 from which the air is delivered upward to the various

burners to which it may be connected. In the particular arrangement illustrated in the drawings, each of the channels 19 delivers its air into the lower portion of a recuperating wall 20, the particular construction of which recuperating wall is shown in my co-pending application for Letters Patent of the United States on improvements in recuperating walls, executed by me as inventor, of even date herewith, filed January 3, 1916, as Serial No. 69,995 said application also being a division of my co-pending application, Serial No. 875,503 filed December 4, 1914. The various air channels 19 of the various ovens of the bench are connected together by a pair of longitudinally extending passages 21 and 22 which extend substantially the entire length of the bench, so that the incoming air may be equalized throughout the entire bench of ovens.

According to the features of the present invention, as particularly illustrated in the drawings herein, I so construct one or more of the spent gas flues that the incoming air 90 travels adjacent to the hot gases in said flues, while, nevertheless, being isolated or cut off from said gases, to thereby transfer a portion of the waste heat from the spent gases into the incoming fresh air. According to the features of the present invention, such heat transfer is secured by so constructing one or more walls of such flues that the incoming air or gas will travel through the body or interior portion of said wall, receiving its heat from the wall, and the wall, in turn, being heated by the hot gas or air traveling adjacent to it.

Figs. 2, 3, 6 and 7 show that certain of the walls of the flues 12 and 13 are provided with a meshwork of horizontally and vertically extending passages 23. In the construction illustrated, this result is accomplished by building the desired walls from blocks which have one or more horizontal and vertical faces centrally recessed, so that, when said blocks are set together, their recesses will coöperate to produce the desired mesh of passages.

Figs. 2 and 3 show the blocks in longitudinal section, whereas Figs. 6 and 7 show the blocks in transverse section. In the arrangement illustrated, I have shown both side walls of each flue as being constructed from blocks of this character, and I have also shown each flue as being provided with another central wall, constructed in similar manner. Manifestly, however, any desired number of such walls might be provided in each flue, or in selected flues, or each of said selected flues might be provided with only one such wall. Therefore, while in the various figures I have shown a construction in which there are two flues for carrying off the spent gases, each of said flues being pro-

vided with three such walls, still it will be understood that a greater or lesser number of flues might be used, and a greater or lesser number of walls of this character 5 might be used in each flue within which a recuperating action is desired.

Adjacent to one end of the flue 12, there is a vertically extending pocket or chamber 24 to which fresh air or gas is delivered by 10 means of a pipe 25. This pocket is in communication with one end of each of the recuperating walls of the flue 12. Adjacent to the other end of the flue 13, and beneath the same is a transverse passageway 26 into 15 which fresh air or gas is delivered by means of the pipe 27. The passageway 26 connects by means of risers 28 with the adjacent ends of recuperating walls of the flue 13. It thus appears that the air or gas within 20 the recuperating walls of the flue 12 travels in the direction opposite to the air or gas within the recuperating walls of the flue 13.

Above each recuperating wall is a longitudinally extending channel 29 into which 25 the heated air or gas from said wall collects. The various channels 29 above each flue are in communication with each other by means of the cross connections 30, shown in Figs. 6 and 7, so that the heated air or gas above 30 each flue may equalize itself from the various recuperating walls of said flue. Corresponding to each of the channels 19, a riser 31 extends upward from the connections 30 of the adjacent flues, and the heated 35 air or gas is delivered to the channel 19 by means of said risers.

Inasmuch as the channels 19 connect together the recuperating walls of the two flues, and inasmuch as the air or gas within 40 the recuperating walls of the two flues travels in opposite directions, it will be evident that an equalization of air or gas pressure will be secured, and there will also be an equalization of recuperative action in the 45 amount of air or gas delivered to each of the channels. Such equalization would not be secured if the air or gas in all of the recuperating walls traveled in the same direction along the length of the bench, and, 50 therefore, it may be considered that I have provided means for causing the air or gas traveling through two or more recuperating walls to so equalize in said walls that the air or gas delivered to the various ovens 55 from said walls will all be at substantially the same temperature or subjected to substantially the same amount of recuperating action.

In the several figures, the foundation pillars are designated by the numeral 32.

It will be observed from a consideration of the foregoing disclosures that I have made provision for the recuperation of heat

between the gases flowing within the passages of the tunnels themselves on the one hand, and the gas or air flowing within the walls of said tunnel on the other hand. Said recuperation may be in the form either of transmission of heat from the air or gas flowing through the tunnel into the air or gas flowing within the walls, or in a reverse direction, although in the particular construction illustrated the recuperation is from the tunnel passages to the gas or air flowing within the walls. It will also be observed 7 that I have provided a construction whereby the amount of recuperation may be increased beyond that amount which would be secured merely by the recuperation in the two opposite walls of the tunnel. Such increased 8 rate or amount of recuperation may be secured by the interposition of a desired number of recuperating partitions within the body of the tunnel itself, although in the particular construction illustrated I have 8! shown only a single partition extending along the central portion of each tunnel.

I claim:

1. In a construction of the class described a foundation having two parallel tunnels, 90 each tunnel having walls, selected ones of said walls having passages for air, connections for the delivery of air to all of said passages, and connections for the delivery of air from all of said passages at selected 95 intervals.

2. In a construction of the class described a foundation having two parallel tunnels, each tunnel having walls, air passages within all of said walls, connections for the delivery of waste gas to the space between the walls of each tunnel, connections for the delivery of air into one end of the air passages of the walls of one tunnel, connections for the delivery of air into the other end of the 10 air passage of the walls of the other tunnel, and connections for the delivery of air from all of said air passages at selected intervals.

3. In a construction of the class described, a foundation having two parallel tunnels, 11 each tunnel having walls, air passages within selected walls of each tunnel, connections for the delivery of gas to the space between the walls of each tunnel, connections for the delivery of air into one end of the air passages of the walls of one tunnel, connections for the delivery of air into the other end of the air passages of the walls of the other tunnel, and connections for the delivery of air from said air passages at selected intervals.

4. In a construction of the class described, a foundation having a tunnel, said tunnel having walls, selected ones of said walls having passages for air, connections for the delivery of air to all of said passages, and con-

nections for the delivery of air from all of said passages at selected intervals.

5. In a construction of the class described, a foundation having a tunnel, said tunnel having walls, air passages within selected walls, connections for the delivery of waste gas to the space between the walls, connections for the delivery of air to said passages, and connections for the delivery of air from all of said passages at selected intervals.

6. In a construction of the class described, a foundation, a plurality of walls therein, air passages within selected ones of said walls, connections for the delivery of air into one end of the air passages of one wall, connections for the delivery of air into the other end of the air passages of the other

wall, and connections for the delivery of air from all of said passages at selected intervals.

7. In a construction of the class described, a foundation, walls therein, there being air passages in selected walls, connections for the delivery of air into one end of the air passages of one wall, connections for the delivery of air into the other end of the air passages of the other wall, and common connections for the delivery of air from the air passages of both walls.

ARTHUR ROBERTS.
